UNITED STATES PATENT OFFICE.

JOSEPH E. MILLER, OF DES MOINES, IOWA.

FORM FOR CIRCULAR CONCRETE CONSTRUCTION.

Application filed April 17, 1924. Serial No. 707,092.

The object of my invention is to provide a form for the making of circular concrete construction work such as concrete pipes or columns.

More particularly, my invention relates to a form comprising a number of sections of substantially uniform size and arranged side by side in circular outline for forming a form for pouring a concrete pipe or the like.

It may be mentioned that drain or sewer pipes are ordinarily made in diameters divisible by 3, that is, drain tiles are ordinarily 27 inches, 30 inches and increase 3 inches from one size to another, and it is my object to provide sections of a form wherein one section removed, will make the difference between a 36 inch pipe and a 39 inch pipe.

Still a further object is to provide on each section of the form a metal plate which is capable of having its arc or curved portion changed so that the same section can be used in making a 24 inch pipe or a 48 inch pipe.

Still a further object is to provide a means on the inner and outer forms for locking the sections together and for drawing them in closed position.

Still a further object is to provide a ring adapted to coat with the forms for causing a tongue to be formed on the upper end of the concrete pipe which is used in making the joint between adjacent pipes.

Still a further object is to make each section of the form channel shaped in cross section so that when placed side by side, the sections will be thoroughly braced and will not bulge or spread apart.

Still a further object is to provide a form for sewer pipe or the like wherein the same forms can be used for making pipe, the walls of which may be of different thickness.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Figure 1 is a top plan view of a number of sections used in forming a complete sewer tile.

Figure 2 is a side elevation of a number of sections showing the locking means for retaining the sections in closed position. 55

Figure 3 is a detail, sectional view taken on line 3—3 of Figure 2 showing the locking means.

Figure 4 is a detail, sectional view taken on line 4—4 of Figure 2. 60

Figure 5 is an enlarged sectional view taken on line 5—5 of Figure 2 showing the inner and outer section forms.

Figure 6 is a detail, sectional view of the bottom ring and one of the sections wherein 65 a pipe of less thickness can be made.

Figure 7 is a top plan view of one of the sections of the form showing the cover plate in one position.

Figure 8 is a view similar to Figure 7 70 with the cover plate shown in another of its positions; and

Figure 9 is a sectional, perspective view of one of the sections of the form.

In the accompanying drawings, I have 75 used the reference character A to indicate generally a section of the form. Each section A includes a bottom reinforcing bar 10 and an upper reinforcing bar 11.

The bars 10 and 11 are channel shaped in 80 cross section and have their front sides slightly curved.

The bars 10 and 11 have fixed thereto a sheet metal plate 12 which has flanges 13 thereon extending substantially at right 85 angles to the main body portion of the plate 12 and adapted to rest against the ends of the bars 10 and 11, as clearly shown in Figure 9 of the drawings. 90

The sections A may be of any length desired and are ordinarily of sufficient width so as to equal 3×3.1416 ; the purpose of which will be hereinafter set forth.

The ends of the bars 10 and 11 are formed with openings 14 through which are extended bolts 15. The bolts 15 extend through elongated slots 16 formed in the flanges 13. 95

The main body portion 12 of the sheet metal plate is formed with a number of openings which register with openings 17 100 formed in the bars 10 and 11 whereby bolts 18 may be extended therethrough for securely holding the plate 12 to the bars 10 and 11.

The bolts 18 are provided with countersunk heads so that the front side of the plate will be smooth.

The section A just referred to is one of a number of outer sections shown in Figure 1 of the drawings.

Sections B made similar to sections A form the inner wall or form for the pouring of the concrete pipe. The plates 12 of the sections B are curved outwardly somewhat, as clearly shown in Figure 1 of the drawings, the purpose of which is to provide a complete circular outline when the sections are placed side by side.

15 The sections, when placed side by side, are connected together by the bolts 15 which extend through two adjacent sections and through the upper bars 11 and the lower bars 10, as clearly shown in Figures 3 and 20 5 of the drawings.

The bolts 15 also extend through the flanges 13 of the sheet 12.

Suitable openings 19 may be formed in the flanges between their bottom and top 25 and when the sections are placed side by side, bolts 20 may be employed for connecting the two adjacent flanges together.

From the construction of the parts just described, it will be seen that the sections 30 can be quickly and easily connected together.

All the sections are connected together as has just been explained, with the exception of the last or connecting sections, and I provide connecting sections referred to by the reference characters C and D. The section C is connected to one side of one of the sections A and the section D is connected to one side of the sections A.

40 The section C is made very much like the section A with the exception that I provide a gear 21 mounted on a shaft 22 which is formed in the two flanges of the reinforcing bar 11.

45 A similar gear 21 and shaft 22 is also formed in the lower bar 10.

The upper ends of the shafts 22 are provided with squared portions 23 for permitting a wrench or crank to be secured thereto for rotating the gears 21. The section C has the upper and lower bars 10 and 11 formed with a rack bar 24 adapted to coact with the gears 21, as clearly shown in Figure 3 of the drawings.

50 A plate 25 is secured to the bars 10 and 11 of the section C and is provided with only one flange 13 and has its other end turned in only a slight distance so as to form a short flange 26, the purpose of providing the short flange 26 is to prevent the same from interference with the rack bars 24 which coact with the gears 21.

Secured to the bars 10 and 11 of the section D is a plate 27 of considerable length,

which has one flange 13 thereon made exactly like the flanges 13 on the plates 12.

The free end of the plate 27 rests against the plate 25 and is permitted to slide thereover when the gears 21 and rack bars 24 are operated.

70 From the construction of the parts just described, it will be seen that by rotating the gears 21, I am able to draw the sections C and D closer together and in turn completely lock the complete outside form for the 75 pouring of a concrete pipe.

Sections C and D are fixed to the sections B, which form the inner wall of the form and operate exactly like the sections C and D referred to in connection with the outer 80 wall of the form.

It will be noted that the plate 27 overlaps the plate 25 a considerable distance so that any adjustment desired, may be obtained for making concrete pipes of various 85 diameters.

In order to form a tongue joint on the lower end of the concrete pipe, I provide a ring 28 which is formed with a shoulder 29 at one end and a shoulder 30 at its other 90 end. A ring 28 of different diameters is used for making pipes of different sizes.

The inner form sections B rest against the shoulder 29 of the ring 28, as clearly 95 shown in Figure 5 of the drawings. The bottom bars 10 may be provided with a downwardly extending flange 31 which rests against the outer edge of the ring 28 for retaining the inner and outer form sections spaced apart for making a hollow pipe, the 100 walls of which are of any predetermined thickness.

When it is desired to make a pipe, the walls of which are of less thickness than that shown in Figure 5 of the drawings, then a lower bar 10 is used which does not have the flange 31 thereon, and in that case, the lower bar 11 abuts against the shoulder 30, as clearly shown in Figure 6 of the drawings.

110 From the construction of the parts just described it will be seen that when the lower gears 21 and rack bars 24 are operated both on the inner and outer wall of the form, then the complete number of sections will be securely held in position against the ring 28.

In order to form a coacting tongue and groove on the other end of the concrete pipe for permitting the pipes to coact with each other when laid end to end as in sewer work, I provide a ring 32. The ring 32 is provided with an upwardly extending annular flange 33.

120 A number of holding straps 34 are riveted to the flange 33 by means of rivets 35. The holding straps 34 have horizontal portions 36 which abut against the inner wall or sec-

tions B of the form. The upper edge of the flange 32 is spaced from the inner form or sections B for permitting concrete to be poured therethrough when the concrete pipe 37 is just about to be completed.

5 The outer edge of the ring 32 rests against the inner side of the sections A.

It will be noted that when the upper gears 21 and rack bars 24 are operated, the 10 sections B and A will be drawn toward each other and held apart in proper position by the ring 32 and the straps 34 thereon.

In order to hold the ring 32 in proper position, I provide each of the straps 34 with 15 an extended horizontal portion 38, which has a hook bolt 39 mounted therein.

The hook bolt 39 is adapted to engage one 20 side of the upper bar 11 of the section A. The hook bolts 39 retain the ring 32 in proper position.

In order to lock the gears 21 and rack bars 24 in proper closed position, I provide a locking pawl 40 for each of the gears 21. The locking pawl 40 is provided with a slot 25 41 through which is extended a locking or set screw 42. The set screw 42 is threaded into a wall 43, which is formed as a part of the casting of the bars 10 and 11, which are used in the sections C and D.

30 The locking pawl 40 is formed with a hand engaging tab 44 whereby the locking pawl 40 may be slid into or out of engagement with the gear 21.

In Figure 3 of the drawings, I have shown 35 the locking pawl 40 in engaged position with the gear 21 and in that case, the parts will be held against any spreading movement.

In Figure 7 of the drawings, I have shown the plate 12 formed in the arc of a 40 circle of comparatively less diameter than that shown in Figure 8 of the drawings.

When a great number of sections A are used, that is, for making a concrete pipe of considerable diameter, then in order to get 45 the outside of the pipe in proper outline, I loosen the center bolt 18 and place a washer 45 between the plate 12 and the upper and lower bars 10 and 11 and then when the bolt 18 is again inserted and tightened, it will retain the plate 12 in position where it will, 50 when placed with a number of other sections operate successfully in connection with the pouring of a pipe of considerable diameter.

55 In Figure 7 the two end bolts 18 are loosened and washers 45 placed thereon so that when the bolts are tightened, the curvature of the plate 12 will be greater than the curvature of the plate shown in Figure 8 of the drawings and in that case the section will conveniently operate in making of pipes of less diameter.

It will be noted that when the plate 12 is bent to form the arc of a circle, as shown 60 in Figure 7 of the drawings, it is necessary

for the flanges 13 to slide somewhat upon the lower and upper bars 10 and 11 and for that reason the elongated slots 16 are provided for permitting the flanges 13 to be moved somewhat and yet bolted to the lower 70 and upper bars 10 and 11.

The plates 12 are formed of bendable material so that various arcs of circles may be formed therefrom.

75

Practical operation.

In the practical operation of my form for concrete construction, I first place the ring 28 upon any suitable support and thereafter mount the inner wall formed of the sections 80 B upon the ring 28 and against the shoulder 29. The lower gear 21 and rack bar 24 are then operated for spreading the sections wherein they will be engaged against the shoulder 29 of the ring 28.

85 After the sections B have been moved against the shoulder 29, then the locking pawl 40 is moved into position where it contacts with the gear 21. The upper gear 21 and rack bar 24, which form the locking device are also operated and then locked in proper position.

The outside wall formed of the sections A is then placed upon the ring 28.

90 When a thick walled pipe is desired, then the flange 31 is arranged to abut against the outer edge of the ring 28. The lower locking device consisting of the gear 21 and the rack bar 24, is then drawn together for causing the flange 31 to securely engage 100 the outer edge of the ring 28.

The upper locking device on the outer wall is then drawn together to just about the proper size. The concrete is then poured in between the inner and outer walls for forming the pipe.

105 After the concrete has been poured in to just about the upper edge of the outer wall of the form, then the ring 32 is placed in position as shown in Figure 5 of the drawings. After the ring 32 is placed in this position, then the locking device on the upper end of the outer wall is tightened for securely holding the ring 32 in position, and at the same time forcing the loose concrete thereagainst.

110 If the form is not completely filled with concrete, the loose concrete can be poured in between the upper edge of the flange 33 of the ring 32 and the inner wall of the form. The upper edge of the concrete pipe 37 can be smoothed off with the upper edge of the flange 33 as a guide.

115 When a concrete pipe with a comparatively thin wall is desired, then the outer wall formed with sections A is placed upon the ring 28 and adapted to engage the shoulder 30, as clearly shown in Figure 6 of the drawings.

120 The outer wall of my form can be used for 125

130

the pouring of pillars in concrete construction work.

One of the advantages of my form is the fact that I am able to add or subtract any 5 one section therefrom for making columns or pipes of various diameters.

Some changes may be made in the construction and arrangement of the various parts of my invention, without departing 10 from the real spirit and purpose of my invention and it is my intention to cover by 15 my claims, any modified form of structure or use of mechanical equivalents, which may be reasonably included within their scope.

15 I claim as my invention:

1. A form of the class described comprising sections, each section comprising a bendable plate having a mold surface and reinforcing flanges along each side of the plate, 20 a reinforcing member positioned at each end of said plate having one of its sides secured to said mold surface and its ends secured to said flanges.

2. A form of the class described comprising sections, each section comprising a bendable plate having a mold surface and rein-

forcing flanges along each side of the plate, a reinforcing member at each end of said plate, openings in said members, and registering openings in the mold surface and 30 flanges of said plate, bolts for extending through said openings and securing said members to said plate, the openings in said flanges being slotted whereby said plates may be adjusted as to curvature without 35 removing the bolts through the flanges thereof.

3. A form for circular concrete construction comprising a bendable plate having a portion of the edges thereof bent at substantially right angles to the body portion whereby reinforcing flanges are provided, reinforcing members at the ends of said plates, bolts for securing said reinforcing members to the body portion and the flanges 45 thereof, slots in said flanges through which said bolts extend whereby washers inserted between said reinforcing members and said body portion for varying the curvature of said plates without removing the bolts 50 through the flanges thereof.

JOSEPH E. MILLER.
